US0D1068879S

(12) **United States Design Patent** (10) **Patent No.:** **US D1,068,879 S**
(45) **Date of Patent:** **** Apr. 1, 2025**

(54) **OPERATING CONSOLE FOR MACHINE TOOL**

(71) Applicants: **DMG MORI CO., LTD.**, Nara (JP);
GILDEMEISTER Beteiligungen GmbH, Bielefeld (DE)

(72) Inventor: **Matus Prochaczka**, Lochau (AT)

(73) Assignees: **DMG MORI CO., LTD.**, Nara (JP);
GILDEMEISTER BETEILIGUNGEN GMBH, Bielfeld (DE)

(**) Term: **15 Years**

(21) Appl. No.: **29/819,083**

(22) Filed: **Dec. 13, 2021**

(30) **Foreign Application Priority Data**

Jun. 15, 2021 (JP) ..... 2021-012789 D

(51) LOC (15) Cl. **15-09**

(52) U.S. Cl.

(57) **CLAIM**

The ornamental design for an operating console for machine tool, as shown and described.

DESCRIPTION

FIG. 1 is a front view of an operating console for machine tool in accordance with an embodiment of my new design; FIG. 2 is a rear view thereof; FIG. 3 is a right side view thereof; FIG. 4 is a left side view thereof; FIG. 5 is a top view thereof; FIG. 6 is a bottom view thereof; FIG. 7 is an enlarged view of portion 7 of FIG. 1; FIG. 8 is an enlarged view of portion 8 of FIG. 3; FIG. 9 is an enlarged view of portion 9 of FIG. 4; and, FIG. 10 is an enlarged view of portion 10 of FIG. 5.

The broken lines shown in the figures depict portions of the operating console for machine tool that form no part of the claimed design. The long dashed and short dashed lines disclosed in the figures are boundary lines and form no part of the claimed design.

1 Claim, 9 Drawing Sheets
